CLAIM

I claim the ornamental design for a wearable blanket, as shown and described.

DESCRIPTION

FIG. 1 is a front perspective view of a wearable blanket, showing my new design;

FIG. 2 is a front view thereof;

FIG. 3 is a rear view thereof; and,

FIG. 4 is a view of the wearable blanket in a position of use around a wearer's torso.

The dot-dash broken line represents a boundary of the claimed design and which forms no part thereof. The broken lines depicting the remainder of the wearable blanket show features that form no part of the claimed design.
